United States Patent Office

Des. 233,433
Patented Oct. 29, 1974

233,433

PRIMER TRAY

Fred A. Huntington, Oroville, Calif., assignor to
RCBS Inc., Oroville, Calif.

Filed Aug. 4, 1972, Ser. No. 277,915

Term of patent 14 years

Int. Cl. D22—05

U.S. Cl. D22—99

Fig. 1

Fig. 2

Fig. 3

Fig. 4

FIG. 1 is a top plan view of the primer tray with cover in place;

FIG. 2 is a side elevation of the primer tray with cover in place;

FIG. 3 is a side elevational view of the primer tray with cover in place with the tray rotated 45° from the position of FIG. 2;

FIG. 4 is a bottom view;

FIG. 5 is a top plan view with cover removed and inverted;

FIG. 6 is an enlarged sectional view taken along the lines 6-6 of FIG. 5.

I claim:

The ornamental design for a primer tray, as shown.
